ENGINE STARTER CONTROL

Paul H. Maurer, Birmingham, Mich., assignor, by
mesne assignments, to Bendix Aviation Corporation,
South Bend, Ind., a corporation of Delaware

Original application April 16, 1935, Serial No.
16,643. Divided and this application December
24, 1936, Serial No. 117,547

6 Claims. (Cl. 290—38)

The present invention relates to engine starter controls and more particularly to a device for energizing by progressive steps an engine starter of the automatic mesh and demesh type so as to secure engagement of the starting mechanism prior to the full energization of the starting motor.

This application is a division of application Serial Number 16,643, filed April 16, 1935, Patent Number 2,073,645.

10 In starting devices of the automatically meshing and demeshing type, energization of the starting motor is caused to move a pinion into engagement with an engine gear and thus establish a driving connection between the starting motor and engine, which driving connection is automatically interrupted when the engine starts, by the overrunning action of the engine gear which returns the starting pinion to idle position. It will be readily understood that the running start 15 of the motor prior to the engagement of the pinion with the engine gear permits considerable kinetic energy to be stored up in the starting motor and connected parts, which kinetic energy is applied to initiate the rotation of the engine 20 gear.

In certain very heavy duty installations such as large Diesel engine units, where powerful starting motors are energized from batteries of comparatively high voltage with very large current consumption, it has been found that the amount of kinetic energy so stored up by the running start is so large that the parts of the drive when properly designed for the most efficient cranking operation 30 may be seriously overloaded when the starter gearing is initially engaged.

It has therefore been suggested to energize the starting motor with less than the full battery voltage during the meshing operation and then to apply the full battery voltage to the motor after 35 the driving connection has been established, the initial energization being merely sufficient to secure the proper automatic engagement of the drive without storing up unnecessarily large amounts of kinetic energy in the motor armature and its associated parts.

It is an object of the present invention to provide a novel starter control of the type stated which is simple and economical in construction 40 and reliable and efficient in operation.

It is another object to provide such a starter control which positively prevents premature energization of the starting motor to its full capacity.

It is another object to provide such a device in 45 which the parts reset themselves during cranking

so that a restart is controlled similarly to an original start.

It is another object to provide such a device in which a resistor is used to modify the initial actuation of the starting motor, and the same element 5 functions to control the time delay prior to full energization thereof.

Further objects and advantages will be apparent from the following description taken in connection with the accompanying drawing in which:

Fig. 1 is a semi-diagrammatic illustration of one preferred embodiment of the invention showing the parts in normal or idle position; and

Fig. 2 is a similar view showing the parts in cranking position.

In the embodiment of the invention illustrated, a two-stage manually operated switch is employed for controlling the starting operation. As here illustrated, the starting circuit originally includes battery 1, lead 2, manual switch 3, lead 4, resistor 5, lead 6 and starting motor SM, resistor 5 being of such value as to cause energization of the starting motor only to a suitable degree for engaging the starting gearing. There is also provided a bridging circuit 7 for short-circuiting the resistor 20 25 5, which bridging circuit is controlled by a magnetic switch 8 comprising a solenoid 9.

Manual switch 3 comprises fixed contacts 11 and 12 and a bridging contact 13 for completing the initial starting circuit. This switch also includes 30 a second pair of fixed contacts 14 and 15 which are closed by final movement of the bridging contact 13 to thereby complete a circuit from battery lead 2 through lead 16 to solenoid 9 which is 35 grounded as indicated at 17.

Means are provided for initially preventing movement of the manual switch 3 sufficient to close the circuit of solenoid 9, here illustrated in the form of a latch member 18 movable into and out of the path of bridging contact 13 by means of a bimetal strip 19 suitably anchored at 21 and arranged to be heated by the resistor 5 when current is passed therethrough. The latch 18 is in the path of the bridging contact 13 when the bimetal is at normal temperatures, and is moved 40 out of the path of said contact to permit full traversal thereof when the bimetal is heated to a predetermined temperature.

In the operation of this embodiment of the invention, actuation by the operator of the manual switch 3 causes contact 13 to connect fixed contacts 11 and 12, thus completing the initial starting circuit through resistor 5 to the starting motor SM whereby the latter is energized to cause engagement of the starting gearing. Further 45 50 55

travel of contact 13 is initially prevented by latch 18. After a predetermined time interval, resistor 5 heats up the bimetal 19 sufficiently to withdraw the latch 18 from the path of contact 13, whereupon further actuation of the manual switch causes bridging of contacts 14, 15 by contact 13, thereby energizing solenoid 9 and causing closure of magnetic switch 8. The resistor 5 is thereby short-circuited and the starting motor fully energized to crank the engine. Resistor 5 and bimetal 19 are thus permitted to cool off, and when the manual switch 3 is released as the engine starts, the parts return to their normal positions as illustrated in Fig. 1.

15 Although but one embodiment of the invention has been shown and described in detail, it will be understood that other embodiments are possible and various changes may be made in the arrangement and construction of the parts without departing from the spirit of the invention as defined in the claims appended hereto.

What is claimed is:

1. In an electrical starting system for internal combustion engines, a battery, a starting motor, 25 a resistor, a circuit including a manually operable switch having two sets of contacts, closure of the first set completing a circuit through the resistor to the starting motor, and closure of the second set causing the resistor to be short-circuited, and a thermostatic latch for preventing closure of the second set of contacts until the resistor has been heated to a predetermined degree.

2. In an electrical starting system for internal combustion engines, a battery, a starting motor, 35 a resistor, a circuit including a manually operable switch having two sets of contacts, closure of the first set completing a circuit through the resistor to the starting motor, and closure of the second set causing the resistor to be short-circuited, a latch normally preventing operation 40 of the switch to close the second set of contacts, and thermostatic means heated by said resistor for withdrawing said latch.

3. In a starting system for internal combustion engines, a starting circuit including a two-stage switch, means whereby operation of the switch to the first stage causes partial energization of the starting system

starting system, means whereby operation of the switch to the second stage causes full energization of the starting system, means preventing operation of the switch to its second stage, and thermostatic means heated by operation of the switch to its first stage for rendering inoperative said preventing means.

4. In a starting system for internal combustion engines, a starting circuit including a resistor, a two-stage switch, means whereby the first operation of the switch closes said circuit through the resistor, and further operation thereof shorts out the resistor, and thermostatic means, controlled by heat from said resistor, for preventing such further operation.

5. In a starting system for internal combustion engines, a starting circuit including a battery, a starting motor with means for engaging and cranking the engine to be started, a manually operable switch and a resistor adapted to limit the energization of the motor to a value suitable for effecting engagement of the cranking means, means whereby initial operation of said switch closes the motor circuit through the resistor, means whereby further operation of the switch causes full energization of the starting motor, means for preventing such further operation of the switch, and means responsive to closure of the motor circuit through the resistor for a predetermined time for releasing said preventing means.

6. In a starting system for internal combustion engines of the automatic meshing type, a starting circuit including a two-stage switch, means whereby operation of the switch to the first stage causes partial energization of the starting system for meshing the starter gearing, means whereby operation of the switch to the second stage causes full energization of the starting system to crank the engine, means for initially preventing such operation to the second stage, and means actuated by the flow of current through the switch in its first stage position for a predetermined time, to render said preventing means inoperative.

PAUL H. MAURER.
